UNITED STATES PATENT OFFICE.

JOHN TOLAND, OF BOSTON, MASSACHUSETTS.

FILTER.

SPECIFICATION forming part of Letters Patent No. 248,897, dated November 1, 1881.

Application filed September 1, 1881. (No model.)

To all whom it may concern:

Be it known that I, JOHN TOLAND, of Boston, of the county of Suffolk and State of Massachusetts, have invented a new and useful Improvement in Filters; and I do hereby declare the same to be described in the following specification, and represented in the accompanying drawings, of which—

Figure 1 is a longitudinal, and Fig. 2 a transverse, section of a filter embodying my invention, the nature of which is defined in the claims hereinafter set forth.

In such drawings, A is a filtering drum or cylinder, formed with internal flanges, *a a*, arranged in it as shown. Within each end of the said drum is screwed a perforated head, B, against a foraminous or woven-wire disk, *b*, resting against the flange *a*. Furthermore, at its middle and extending around the drum A is a projecting flange, *c*, having a male screw-thread cut on its periphery, to engage with a circumscribing flange, *d*, provided with a corresponding female screw-thread, and projecting from the inner surface of a cylindrical case, C. The drum A is arranged concentrically within the case C, there being a space, *e*, between the two, and against each end, as well as about the periphery of the drum A. The drum C, however, has a flange or annular partition, *f*, arranged in it for the flange *c* to abut against. One of the heads *g g'* of the case C I adapt to the body of the case, so as to be removable therefrom, in order to enable the filtering-drum to be inserted in or removed from the case. The said removable head is marked *g'*, and screws into the case. Furthermore, there are jointed to the case C the bodies *h* of two three-way cocks, D D, each of such bodies communicating with the space *e* by two ports, *i k*, arranged with the partition *f* in manner as shown in Fig. 1. The hollow plug *l* of each cock has two educts, *m* and *n*, arranged in it in manner as represented, and there is to each of the cocks a tubular projection, *E*, having a female screw-thread cut in it, as shown at *o*, such being to enable the filter to be coupled to pipes of conveyance and discharge of the fluid to be filtered. On turning the plugs so as to bring their educts *m* to open into the two ports *k*, water passing under pressure into the upper cock will flow therefrom through the

upper port *k*; thence into the space *e* to the left of the partition *f*; thence lengthwise through the filtering-drum A, duly charged with charcoal or other suitable filtering material; thence into the space *e* to the right of the said partition; thence through the lower port *k* and into the lower plug *l*, from whence it will escape by the passage *n* and port *p*, each three-way cock having such a port *p* arranged in it, as shown in Fig. 1. By revolving each plug so as to put its port *n* in communication with the port *i* of the cock the port *m* will open into the port *p*, whereby the course of the water or fluid through the filtering-drum will be reversed. So, in putting in communication the ports *m* and *k* of the upper cock and the ports *n* and *i* of the lower cock the water or fluid will flow freely through the case C without going through the filtering-drum A.

From the above it will be seen that with the described filter we have means of causing water to flow in either of two directions through the drum A, or to pass through the filter without going through such drum. Thus we can, as occasion may require, cleanse the filter of any deposits left therein by the water or fluid.

In the place of the three-way cocks, I contemplate sometimes employing mechanical equivalents—such as valves, for instance—though I consider the cocks as preferable thereto.

What I claim as my invention is as follows:

1. The combination, with the case C, provided with the internal screw-flange, *d*, and the flange or partition *f*, and with the two three-way cocks D D, adapted to such case, as described, of the internal filtering-drum, A, having the screw-flange *c*, and arranged within the case C, substantially in manner as set forth, all being to operate as explained.

2. The combination of the tubular coupling-projections E E, applied to the three-way cocks, with such cocks and with the case C, provided with the flanges *d* and *f*, and filtering-drum A, having flange *c*, constructed, arranged, and adapted substantially as explained.

JOHN TOLAND.
